ATTORNEYS.

UNITED STATES PATENT OFFICE

HARRY W. HESS, OF LOS ANGELES, CALIFORNIA

CARBURETOR NOZZLE

Application filed June 6, 1927. Serial No. 196,921.

This invention relates to improvements in carburetor nozzles, sometimes termed aspirating tubes or nozzles.

The invention has for an object the provision of an aspirating tube adapted to give a correct proportion of air to gasoline throughout the entire speed range of the motor, and whereby one is able to secure the desired idling period of the motor without loading the said motor.

Another object is the provision of an aspirating tube which is simple of construction, easily installed in existing carburetors, and which will render the said carburetors more efficient and satisfactory.

Other objects include the provision of an aspirating tube for carburetors which will allow an internal combustion motor with which said carburetor is associated to operate more perfectly and with a minimum of gasoline consumption, thus lowering the operating cost of said motor.

Other objects include simplicity of construction, foolproofness in operation, and general superiority and efficiency in use and service.

With the above and other objects in view, the invention consists in the novel and useful provision, formation, construction, association and relative arrangement of parts, members and features, all as shown in a certain embodiment in the accompanying drawing, described generally, and more particularly pointed out in the claims.

In the drawing:

Fig. 1 is a fragmentary and vertical sectional view of a carburetor embodying the improved invention;

Fig. 2 is a vertical sectional view of the improved aspirating tube for the carburetor;

Fig. 3 is a cross-sectional view on the line 3—3 of Fig. 2;

Fig. 4 is an enlarged cross-sectional view of the metering valve head and seat member of the aspirating tube being in section on the line 4—4 of Fig. 3; and

Fig. 5 is a vertical sectional view of the metering valve head and seat member, the aspirating tube being shown in section on the line 5—5 of Fig. 3.

Corresponding parts in all the figures are designated by the same reference characters.

Referring now with particularity to the drawing, the aspirating tube nozzle will be first described followed by a description of its relation relative to other parts of the carburetor.

The aspirating tube is shown in vertical section in Fig. 2, and the same is designated as an entirety by A. The said member includes first and second tubular members a and b, concentrically arranged with the periphery of the tube b spaced slightly from the inner surface of the tube a. Both tubes are formed with bell ends, or mouths, 1 and 2 respectively. The tube b does not extend throughout the length of the tube a in the present embodiment of the invention, although it might do so under certain operative conditions. The tube b is provided with a base member 3, secured within the tube a. In the present instance it will be seen that the bell mouth or end 2 of the tube b extends slightly beyond the confines of the bell mouth 1 of the tube a. What may be termed an expansion chamber 4 is provided as between the base 3 and the inner confines of the tube a. The base 3 is provided with one or more orifices 5, permitting communication between the annular space included between the tubes a and b and the expansion chamber 4. Furthermore, one or more orifices 6 and 7 extend radially through the tubes a and b, and which orifices may or may not be in alignment. It will be noted that the orifices 6 and 7 are above the base 3, and that the orifices 6 communicate with the annular space between the tubes a and b, while the orifices 7, if more than one is used, extend between the annular space included between the tubes a and b and the interior of the tube b. It will be noted that the base 3 closes the bottom portion of the tube b, whereby the tube has no direct communication with the expansion chamber 4, other than by way of the orifices 5 and 7. In order to make this particular aspirating tube adaptable to different carburetors, I have provided a peripheral flange 8 on the tube a.

As showing the adaptation of the present

aspirating tube to a carburetor such as is used on the Hudson motor cars, the said carburetor includes the usual seat member 9, for a metering valve head 10. This metering valve head is provided with one or more primary air passages 11, and the said head is screwthreaded to a metering valve stem 12, as shown at 13. This metering valve stem is provided with a longitudinal orifice, called the fuel metering orifice, 14, and fuel is permitted to pass through said metering orifice 14 under control of a metering pin 15. The aspirating tube or nozzle is locked as between the end of the metering valve stem and the metering valve head, when the metering valve head is screwthreaded to the stem. It will be noted that the bell ends of the tubes *a* and *b* extend into a conical opening 16 in the metering valve head, and that the primary air passages 11 terminate in one instance adjacent the orifices 6 of the tube *a*. It is, of course, understood that the air inlet would communicate with the chamber 17 to supply air to the primary air passages 11.

25 The various uses and advantages of this aspirating tube are as follows:

This tube involves the principle of dual viscosity as related to the passage of air, one passage of air passing around the outside 30 of the tube *a*, while a second passage of air passes through the orifices 6 in said outer tube *a*, and through the orifices 7 in the tube *b*. The gaseous fluid is allowed to expand in the expansion chamber 4, to give an equal distribution of this expanded fluid before such gaseous fluid is permitted to pass through the orifices 5. In the present instance the orifices 5 are equidistantly spaced, so that a viscosity is assured as between said gaseous fluid and 40 the two streams of air, which experiment has indicated gives a correct proportion of air to gas throughout the entire speed range of the motor.

It is obvious that various changes and 45 modifications may be made in practising the invention in departure from the particular showing, without departing from the true spirit of the invention.

Having thus disclosed my invention, I 50 claim and desire to secure by Letters Patent:

A nozzle device for carburetors comprising a tubular body having an exterior flange and an interior tubular member provided with a bottom wall having perforations and 55 forming a fuel expansion chamber at the lower end of the nozzle, said tubular body and said interior tubular member each having radially disposed openings located in the same plane and in registering relation and 60 said radial openings being located in staggered relation to said perforations in the bottom wall of the tubular member.

In testimony whereof, I have signed my name to this specification.
